Asbury Hamilton

By *Goodwin Smith* Attorney

UNITED STATES PATENT OFFICE.

ASBURY HAMILTON, OF BROOKLYN, NEW YORK.

MOP.

1,333,021.

Specification of Letters Patent.

Patented Mar. 9, 1920.

Application filed August 21, 1919. Serial No. 318,899.

To all whom it may concern:

Be it known that I, ASBURY HAMILTON, a citizen of the United States, residing at Brooklyn, in the county of Kings and State 5 of New York, have invented certain new and useful Improvements in Mops, of which the following is a specification.

My invention relates to improvements in mops, and has particular reference to a 10 frame for holding the mop head.

An important object of the invention is to provide a mop head frame, which is formed of a single section of suitably flexible or resilient wire, bent for providing a socket to 15 receive the handle of the mop and opposed clamping members to receive the mop head therebetween and detachably hold the same in place.

A further object of the invention is to 20 provide a device of the above mentioned character which is extremely simple and inexpensive to manufacture.

Other objects and advantages of the invention will be apparent during the course 25 of the following description.

In the accompanying drawings forming a part of this specification, and in which like numerals are employed to designate like parts throughout the same,

30 Figure 1 is a side elevation of a mop embodying my invention,

Fig. 2 is a perspective view of the mop head frame, and,

Fig. 3 is a horizontal section taken on line 35 3—3 of Fig. 1.

In the drawings, wherein for the purpose of illustration is shown a preferred embodiment of my invention, the numeral 5 designates the mop head frame as a whole, which 40 is triangular with its base arranged forwardly. This frame is preferably formed of a single section of suitably stiff and resilient wire, which is coiled at the apex of the triangle, forming turns 6, which constitute a socket, for the reception of the forward end of the handle 7, as shown. This socket may be secured to the handle by frictional engagement alone or the same may be otherwise attached thereto, if desired.

50 The section of wire from which the frame 5 is made, is bent at points 8, providing opposed substantially parallel clamping elements or arms 9, carried by the forwardly diverging sides 10. These arms 9 are provided at their ends with transverse exten-

sions 11, to enter the corner sockets at 8, such transverse extensions being provided with longitudinal keepers 12, at the ends thereof, which engage the opposite sides of the arms 10.

The numeral 13 designates the strands of a fibrous mop head, carried by a back 14. This mop head is arranged between the arms 9, as shown.

In operation, the mop head is retained 65 between the clamping elements 9, which exert a sufficient yielding action thereon, the keepers 12 normally preventing the lateral displacement of these clamping elements. To remove the mop head, the side arms 10 70 are moved apart, so that the keepers 12 disengage the corner sockets 8, thereby rendering the ends of the arms 9 free from connection with the side arms. The mop head may then be readily removed.

It is to be understood that the form of my invention herewith shown and described is to be taken as a preferred example of the same, and that various changes in the shape, size, and arrangement of parts may be resorted to without departing from the spirit 80 of my invention, or the scope of the subjoined claims.

Having thus described my invention, I claim:

1. A mop of the character described, comprising, a mop head frame of substantially triangle form, such frame being formed of a single section of wire, said section of wire being coiled at its upper apex to provide 90 a socket for the reception of the handle of the mop, said frame embodying forwardly diverging side arms which are bent at their forward ends to provide corner sockets and opposed clamping elements, transverse extensions carried by the free ends of the clamping elements to enter the corner sockets and having longitudinal keepers, and a mop head held between the clamping elements.

2. A mop of the character described comprising, a substantially triangular mop head frame embodying forwardly diverging side arms bent at their forward ends to provide corner sockets and oppositely arranged 105 clamping elements which constitute the base of the triangle, transverse extensions carried by the free ends of the clamping elements to enter the corner sockets and having longitudinal keepers, a mop head held 110

between the clamping elements, and means to secure the frame to a handle.

3. A mop of the character described comprising, a frame including spaced sides which are bent at their ends providing transverse opposed clamping elements and sockets at the inner ends of the elements, transverse extensions carried by the free ends of the clamping elements and having longi-

tudinal keepers, and means for securing the frame to a handle.

In testimony whereof I affix my signature in presence of two witnesses.

ASBURY HAMILTON.
